United States Patent [19]
Sheps

[11] **Patent Number: Des. 310,207**
[45] **Date of Patent: ** Aug. 28, 1990**

[54] **RETRACTABLE AUTOMOTIVE BATTERY CABLE HOUSING**

[75] Inventor: **Martin Sheps, Poway, Calif.**

[73] Assignee: **Westway Products Corporation, San Juan Capistrano, Calif.**

[**] Term: **14 Years**

[21] Appl. No.: **246,537**

[22] Filed: **Sep. 19, 1988**

[52] U.S. Cl. **D13/184; D8/359**

[58] Field of Search .... **D13/126, 133, 184; D8/358, 359; 191/1 R, 12.4; 242/47.5, 96**

[57] **CLAIM**

The ornamental design for a retractable automotive battery cable housing, as shown and described.

DESCRIPTION

FIG. 1 is an upper front perspective view of the retractable automotive battery cable housing showing my new design;

FIG. 2 is a lower rear perspective view thereof;
FIG. 3 is a front elevational view thereof with the phantom lines depicting solely environmental structure and forming no part of the claimed design; and

FIG. 4 is a top plan view thereof with the phantom lines depicting solely environmental structure and forming no part of the claimed design.
